UNITED STATES PATENT OFFICE.

JOHN R. PAINTER, OF READING, PENNSYLVANIA, ASSIGNOR TO ORR,
PAINTER & CO., OF SAME PLACE.

DESIGN FOR COOK-STOVES.

Specification forming part of Design No. 7,461, dated May 26, 1874; application filed May 12, 1874.
[Term of Patent 7 years.]

To all whom it may concern:

Be it known that I, JOHN R. PAINTER, of the city of Reading, in the county of Berks and State of Pennsylvania, have invented a Design for Cook-Stoves, of which the following is a specification:

The nature of my design is fully represented in the accompanying photographic illustrations, to which reference is made.

A represents the body of a flat-top cooking-stove, whose fire-doors B B, side doors B¹, and oven-doors B² are ornamented as follows: In the center of the raised panel C of all the doors there is a raised ellipse or egg-formed projection, a, surrounded by a bead, b, which has raised dots c. Outside of the bead b is an ornament consisting of pointed leaves d, the outline of their points forming an ellipse, also small pointed ornaments d'. Similar pointed ornaments surround the bead b on all the doors except the side doors B¹. At the extreme edges of the panels C there is an interlaced border, e, which has small dots between

the interlacings. There are corner ornaments f, which connect with the interlaced borders. The back plate D of the stove has panels E E E, formed by interlaced borders e, similar to those on the doors.

What I claim as my invention is—

1. The design for doors of cook-stoves, consisting of the raised ellipse, or egg-formed projection a, surrounded by a bead, b, with raised dots c, the pointed leaves d, and small pointed ornaments d', substantially as described.
2. The design consisting of interlaced border e of the doors, having small dots between the lacings, in combination with the corner ornaments f, substantially as set forth.
3. The design for the panels E of the back plate D, formed by the interlaced borders e, substantially as described.

JOHN R. PAINTER.
